UNITED STATES PATENT OFFICE.

JOHN H. HUFF, OF FRESNO, CALIFORNIA.

BROODER.

No. 802,693.

Specification of Letters Patent.

Patented Oct. 24, 1905.

Application filed June 6, 1905. Serial No. 263,942.

To all whom it may concern:

Be it known that I, JOHN H. HUFF, a citizen of the United States, residing at Fresno, county of Fresno, and State of California, 5 have invented certain new and useful Improvements in Brooders, of which the following is a specification.

My invention relates to brooders.

The object of my invention is the provision 10 of a brooder of simple and cheap construction which will be easily portable, having hot-water tanks and means for circulating hot water therein, together with novel and improved curtains and means for securing them 15 to the hot-water tanks and for retaining the chicks, whereby the most satisfactory heating effects and retention of the heat will be obtained.

Having the foregoing objects in view, the 20 invention consists in those improved features and novel combinations of parts the construction of which appears more fully hereinafter, while the patentable novelty is recited in the appended claims.

25 In the accompanying drawings, Figure 1 is a side elevation of the complete brooder; Fig. 2, a longitudinal section thereof; Fig. 3, a horizontal section on line 3 3 of Fig. 1, and Fig. 4 a perspective detail of one of the brood- 30 ing-receptacles.

One or more metal tanks 1, (preferably two being employed,) which are by preference circular in form, are used, these tanks having depending circular flanges 3 below their bot- 35 toms 2, and to the flanges 3 are connected legs 4 for supporting the brooder.

The numeral 5 represents a heating-drum having a central tube 6, and this heating-drum is connected by pipes 7 and 8 to the upper and lower portions of the respective hot-water tanks 1, so that the water heated in the drum 5 circulates through the tanks 1 and through said drum 5. A suitable lamp or heater 9, which will be supported somewhat 40 below the legs 4, has its chimney received in the tube 6. A ventilating and heat-deflecting cap 10 is fitted on the top of the heating-drum 5 to not only give a proper draft, but also to better retain the heat. The tanks 1 are connected to the drum 5 by braces 11, and the tanks and drum are preferably cov- 45 ered with asbestos or other heat-non-conductor. The upper portions of the water-tanks

1 can be conveniently filled or the water removed therefrom through pipes 12, closed by 55 caps 13.

The brooding-receptacles comprise a circular ring frame or band 14 and a cloth top 15, which may be of flannel or other suitable fabric and connected to the ring or frame in 60 any preferred manner, one desirable way of effecting the connection being the provision of openings 16 in the ring or frame to receive a cord, wire, or thread 17, passed through the edge of the fabric 15. When the brooding- 65 receptacle is in position, the band frame or ring 14 fits tightly within the flange 3 and up against the bottom of the heating-tank, the cloth top 15 being located between the band or frame and the flange 3 of the heating-tank 70 and sagging or depending loosely, so as to properly cover the chicks.

Suitable hooks or fastening means 18 are provided on the outside of the tanks 1, to which are connected flannel or other suitable cloth 75 strips 19, which depend and touch the surface on which the brooder is supported, and thus inclose the brooding-chamber and permit the chicks to pass in and out thereof.

When the lamp is lighted, the heat will raise 80 the water in drum 5 to the proper temperature and cause it to circulate freely in the heating-tanks 1, and the heat being conveyed to the bottoms 2 and flanges 3 is diffused within the brooding receptacles or chambers 85 and properly warms the chicks.

Having thus described my invention, what I claim as new, and desire to secure by Letters Patent, is—

1. In a brooder, the combination with a heating-tank having a depending flange and means for supporting the tank, of a brooding cloth or fabric, and a frame for holding parts of said brooding cloth or fabric against the inside of the flange aforesaid. 90

2. In a brooder, the combination with a heating-tank having a depending flange and means for supporting the tank, of a brooding cloth or fabric, a frame for holding parts of said brooding cloth or fabric against the inside of the flange aforesaid, said brooding cloth or fabric depending freely from the flange and forming the vertical walls of the brooding-chamber. 100

3. In a brooder, the combination with a heating-tank having a depending flange, of a cloth 105

or fabric located within said flange and forming the top of a brooding-chamber, a frame fitted in and against the flange and holding the said cloth or fabric in position, said cloth or fabric depending from the flange and forming the vertical walls of the brooding-chamber.

In testimony whereof I hereunto affix my signature in presence of two witnesses.

JOHN H. HUFF.
